MACHINE FOR AUTOMATICALLY PUNCHING
CONVERTER TUYÈRESGordon B. Forbes, Salt Lake City, Utah, assignor
to American Smelting and Refining Company,
New York, N. Y., a corporation of New Jersey

Application October 17, 1944, Serial No. 559,052

25 Claims. (Cl. 266—42)

1

This invention relates to the cleaning of converter tuyères and, more particularly, to an improved machine for automatically punching the tuyères of converters of the type employed in smelting operations.

It is common practise to remove impurities from metals by treatment in a converter, the molten metal being blown by forcing air into the melt through tuyères arranged along a side of the converter. During this blowing operation, encrustations are unavoidably formed at the inner ends of the tuyères which, if not removed, impede or shut off the flow of air through the tuyères thereby impairing the converting operation.

It has been conventional practise to remove these encrustations manually by inserting a bar in the outer end of the tuyère and thrusting it against the encrustation to break the latter away. While the desirability of providing a machine to perform this work in an automatic and continuous manner has long been recognized and various mechanisms have been proposed, no generally acceptable machine for performing the task commercially has been devised, insofar as applicant is aware.

According to the present invention, a machine is provided for successively and automatically punching converter tuyères which has sufficient flexibility of operation to clean misaligned tuyères whereby a commercially practical automatic punching machine is provided. While the invention is illustrated and described with particular reference to a machine for punching tuyères on the ordinary rotary converter, such as commonly used for blowing copper matte, it will be understood that the principles may be applied to converters of other types.

The utility of the automatic punching machine of the invention is enhanced by a number of characteristic features embodied by it. Some of the more important characteristics are:

(1) No part of the automatic punching machine is directly connected with the converter. This arrangement permits turning and tilting of the converter to charge, blow, skim, discharge, etc., without having the punching mechanism interfere with the converter or stack supports.

(2) The punching machine is mounted separately from the converter proper and embodies means for aligning the punching tool with the tuyères when converter returns to blowing position after skimming or emptying the metal into ladles.

(3) The automatic puncher comprises means

2

for compensating for any misalignment of tuyères which occurs in practically all converters after they have been in use a short while.

(4) Provision is made for interlocking the converter controls with the automatic punching mechanism whereby once the punching operation has begun the converter cannot be moved, the arrangement being such that in the event of a punch bar sticking, interlocked controls prevent any movement of the converter until the bar is free of the tuyère.

(5) Provision is made wherein should the automatic punching mechanism of the machine become inoperative for any reason, emergency operable means are present for moving the automatic machine to one side to permit manual punching of the tuyères until the malfunctioning of the offending member has been remedied.

(6) Embodied in the machine are means operable automatically to move the punching machine proper from tuyère to tuyère successively, the punching rod and prime mover means being yieldably mounted on a carriage which is moved along independent of the converter. The carriage is also located automatically with respect both to the longitudinal and the circumferential position of the tuyères.

(7) Provision is also made wherein the reciprocating punch rod may be adjusted to make a shorter stroke as the inner wall of the converter and the end of the tuyère erode away with continued use.

Although the novel features which are believed to be characteristic of this invention will be particularly pointed out in the appended claims, the invention itself, as to its objects and other advantages, and manner in which it may be carried out, may be better understood by referring to the following description taken in connection with the accompanying drawings forming a part thereof and illustrating a preferred embodiment, in which

Fig. 1 is a rear elevation illustrating an embodiment of the invention wherein one puncher is mounted on a carriage and adapted to move in position to punch the tuyères successively, the converter and tuyères being shown diagrammatically;

Fig. 2 is an end elevation of the tuyère punching machine illustrated in Fig. 1 showing the puncher, carriage and track arrangement for circumferential travel of carriage relative to the converter, the converter being shown partly broken away;

General arrangement

Referring to the drawings, and particularly Figs. 1, 2 and 5 thereof, there is shown a rotary converter, generally designated by 10, having a longitudinally spaced row of tuyères 11 required to be cleaned of encrustations at their inner ends. To accomplish this a tuyère puncher 12, illustrated in detail in Figs. 3 and 4, is suitably mounted on a carriage 15 movable longitudinally of the converter on the machine bed 18. The bed 18 in turn is movably supported within spaced guides 19 which are fastened at opposite ends in the horizontally extending puncher supporting frame generally designated at 21 as illustrated in Figs. 1 and 2. Thus, both horizontal, as well as radial, movement of the puncher as a unit circumferentially of the converter is provided. Suitable rollers 25 mounted at each end of the bed 18 are arranged to engage the guides 19, the bed 18 and associated puncher mechanism being adjustably supported within the guides 19 by cables 27 which extend over the sheave wheels 28 to counterweight 29 as shown in Fig. 1. Counterweight 29 is fastened through cable 31 to the piston rod 32 actuated by the hydraulic cylinder 35, the counterweight being enough lighter in weight than the bed 18 and associated puncher mechanism to permit the bed to move downwardly until it makes contact with the lower part of the frame 21 in which position the hydraulically operated piston rod 32 of cylinder 35 will have reached the upper limit of its stroke.

As illustrated in Figs. 1 and 2, the cable carried punching machine bed 18, guides 19, puncher supporting frame 21, tuyère puncher 12 and associated operating mechanism is supported and moved as a unit on the wheels 38 and 39 resting on track 40. The wheels 39 are drivingly connected to the gear rack 42 which is reciprocated

by the piston rod 43 actuated by the hydraulic cylinder 44 which in turn is operatively controlled by a solenoid valve 45. When it is desired to move the punching machine away from the converter for making repairs or for any other reason, the valve 45 is operated to move the machine from the position shown in full lines in Fig. 2 to that illustrated by broken lines.

Embodying in the machine bed 18 is a manual punching platform 50 which is movably mounted on the track 52 by flanged wheels 53 as shown in Figs. 1 and 2A. When manual punching of the tuyères is to be carried out the automatic puncher is moved away from the converter to the dotted line position shown in Fig. 2 and the platform 50 is extended toward the converter, from dotted line position to that shown in full lines in Fig. 2A, the height of the platform being adjusted by operation of the hydraulic cylinder 35. This provision for quick conversion of the machine from automatic to manual punching is advantageous inasmuch as in certain types of converting, for instance copper blowing, there are certain stages in the converting operation where it is important that no delay or interference with the completion of the blowing treatment be permitted. Should this occur by reason of the failure of any part of the automatic punching mechanism, the machine can be quickly moved aside and the platform 50 positioned to allow the tuyères to be cleaned manually and the blowing operation continued until the charge is finished.

In the preferred arrangement, as illustrated in Fig. 1, fluid pressure for actuating the hydraulic cylinder 35, to move the bed 18 and associated puncher mechanism vertically, is effected by a hydraulic pump 57 which withdraws oil from the sump 58 and supplies it to the hydraulic cylinder 35 through a suitable piping and valve arrangement, as shown, the pump being driven by motor 59. The hydraulic pump 60, as shown to the right on Fig. 1 and driven by motor 61 while in communication with the oil sump 63, is adapted to supply hydraulic fluid pressure to the horizontal motion cylinder 65 through suitable piping and valve mechanism. Relief valves 67 on pump 57 and 68 on pump 60 are provided to control the oil pressure admitted to their respective cylinders. Provision is made for moving the tuyère puncher 12 longitudinally of the converter adjacent the row of tuyères 11 and automatically punching each tuyère in succession. Cams 70, which are preferably located on the punching machine bed 18, as illustrated on the drawings, are utilized to control the movement and operation of the puncher. A cam is provided for each tuyère, the cam being adjustably positioned on the machine bed so that the puncher carriage 15 engages it as the carriage is moved along. Engagement of a cam opens an electrical circuit in the control system, as hereinafter described, whereupon the carriage is brought to a stop in position, adjacent the tuyère to be punched, to permit the puncher to engage and punch the tuyère. Movement of the puncher along the machine bed 18 is effected by a cable 72 to which the puncher carriage is suitably fastened, as by using clamps 73 illustrated in Figs. 6 and 7. Cable 72 is reeved over sheaves 74, located at opposite ends of the machine bed 18, and is wound on a drum 75, using a take-up sheave 76 to maintain the cable taut. The cable drum 75 is rotated on its axle shaft 76 by pinion gear 77 keyed thereto, the pinion being

suitably held in mesh with the rack 79 which, in turn, is connected to and reciprocated by the piston rod 80 of the horizontal motion cylinder 65. Oil under pressure for operating cylinder 65 is admitted to the cylinder by the solenoid actuated inlet valve HS-2 or HS-3 depending on the direction in which it is desired to move the puncher 12. Exhaust oil flows from the hydraulic cylinder 65 through solenoid operated valves HS-1 or HS-4 and is returned to the oil sump tank 63.

Construction and operation of tuyère punching mechanism

Referring to Figs. 3 and 5, the carriage 15 and associated puncher mechanism 12 are supported for horizontal movement on the track 88 by double-flanged wheels 89, track 88 being mounted on the machine bed 18, which in turn is supported for vertical movement as shown in the drawings. Elongated angle members 91 secured to the inner side of the bed 18 are provided to prevent derailment of the carriage. The puncher carriage 15 is journaled to the axles 93, as shown in Fig. 3. Attached to the top plate-like portion 94, by a king bolt 95, is a secondary punching cylinder 100. As illustrated in Fig. 3, this cylinder is mounted on the plate 94 so that the longitudinal axis of the cylinder is inclined to the horizontal, the cylinder being prevented from turning by a stud bolt 102 which secures an integral L-shaped flange portion 103 of the cylinder to the plate 94. By employing this arrangement, the punching mechanism can be swung around at right angles to the converter, after removing bolt 102, thus making the mechanism readily accessible for repairs.

Punching cylinder 100 is preferably operated by compressed air and is of conventional type construction with cylinder heads adapted to accommodate electric switches P-4 at one end of stroke and S-2 and H-3, S-5, M-1, P-3 at other end of stroke, all of which are actuated by piston 105 at the end of its respective strokes. The piston rod 107 which is actuated by movement of the piston 105 is connected at its outer end, by a threaded portion 108, to a slidable member 109 upon which is yieldably mounted the primary punching cylinder 110. This cylinder is constructed similarly to cylinder 100 being actuated by compressed air and arranged to reciprocate the tuyère punch rod 112. The cylinder is inclined to the horizontal in conformity to that of the tuyère, as illustrated in Fig. 3. By adjusting the nuts 115 and 116 to position the lug 118, which is integral with the slidable base 109, the end position of the punch rod 112, relative to the inner opening of the tuyère pipe 120 in the converter at the end of its punching stroke, may be changed. With a new tuyère pipe, for example, the position of the member 109 may be as indicated in full lines in Fig. 3; whereas, after the tuyère has worn away, the member 109 may be adjusted to compensate therefor, taking the position shown by the dotted lines on Fig. 3. In this way the punch rod 112 is not forced out into the molten metal in the converter any more than necessary to properly clean the tuyère. This adjustment feature substantially increases the service life of the punch bar inasmuch as less of the bar is subjected to the heated charge during the punching operation. Moreover, utilizing the arrangement illustrated, punch rods of one standard length may be stocked for any number of punching machines. Aside from these

advantages, the two cylinder punching mechanism lengthens the service life of the packing glands of the punching cylinders 100 and 110 due to proportioning the overall length of punching stroke between the two cylinders.

As illustrated in Figs. 3 and 4 the slidable base 109, supporting the cylinder 110, is retained in position by a dove-tail guide 125 which preferably forms an integral part of cylinder 100 as shown in Figure 4. Cylinder 110 is yieldably supported with respect to the member 109 by radial disposed springs 128, the forward end of the cylinder being suitably mounted in a spherical bearing 130 providing a universal joint. The spherical bearing 130 is retained in the socket 132 which includes four radial arms 135 arranged to fit in holes 137 and around which is placed the coil springs 128. This construction provides an arrangement whereby should the tuyère pipe 120 be misaligned, as frequently occurs in converter practise, with the assistance of a funnel-shaped tuyère entry piece 140, the punching cylinder 110 will move against its spring support and align itself with the misaligned tuyère pipe to permit punching of the tuyère which otherwise would be impossible except manually. The funnel-shaped entry opening defined by the guide 140 is such as to provide for the greatest misalignment that a tuyère may acquire during use. It will be understood, of course, that yieldable means other than springs, for example rubber or the like, may be used in mounting the punching cylinder on the base member 109, the important thing being to provide for universal movement of the punching tool when punching tuyères. Further, by making the punching tool yieldable along its longitudinal axis, through the cylinder and spring mounting, a more durable punching mechanism is provided and less shock and vibration is transmitted from the punching tool to the associated machine elements during use. Punching cylinder 110 is constructed similarly to cylinder 100 with cylinder heads adapted to accommodate electric switches P-5 at one end of its stroke and P-7 at the other end, all of which are actuated by the piston 145 at the ends of its respective strokes. Punch rod 112 is suitably attached to the piston 145 and is reciprocated in the tuyère to clean away the crust from the inner end of the tuyère pipe, as shown in Fig. 3.

Description of electrical control circuit for punching tuyères using a single puncher

Referring to the electrical control wiring diagram of Fig. 8 and Figs. 1 to 7 for operating a single tuyère puncher on a converter, the electrical circuit comprises four parts, each of which is interlocked so that a certain sequence of operations is required before any part can bring about actuation of its particular mechanism. This sequence is as follows:

Assume the converter is in operating position with puncher 12 stationary and horizontal motion cylinder 65 at the end of its stroke, motor 65 controls F-1 and R-1 being both de-energized (Fig. 8). The air valve 5 in conduit 6, shown in dotted lines, through which air is fed to the converter, is open and contacts U-1 are closed energizing UC-1 closing contacts U-3, horizontal alignment contacts H-5 (Fig. 8) being not quite in contact. When air flow through conduit 6 decreases to a predetermined value, due to the formation of crusts on the inner end of a tuyère or tuyères, contacts U-2 close by operation of 75 the manometer tube 7 and electrical circuit is

established energizing coil UC-2 closing contacts H-1. This starts the motor 61 of pump 60 and oil is pumped to the horizontal motion cylinder 65 until H-1 is again opened. Inlet valve HS-2 and the exhaust valve HS-4 on the horizontal motion cylinder 65 are now open, being energized through H-1 H-3, H-2, H-4 and H-7. The piston rod of cylinder 65 and switch striker 150, Fig. 5, will now start to move away from H-10 and will continue to move in this direction until the striker 150 closes switch H-11. During this time H-1 is held closed by HC-8 and 9 through circuit H-8 and H-9 insuring that the piston rod 80 of cylinder 65 will complete its full stroke from H-10 to H-11 should the contact U-2 be broken by restored air flow.

As described, horizontal movement of the rod 80 rotates the drum 75 moving the cable 72 and attached tuyère puncher 12 past the tuyères. This horizontal motion is interrupted at each tuyère long enough for the puncher to operate and clean the tuyère pipe. When the puncher reaches a tuyère and engages its respective cam 70, contacts H-5, H-4, H-12, H-13 and H-14 being closed, holding coil HC-5 is energized opening H-2 thus de-energizing and closing solenoid valves HS-1, HS-3, HS-2 and HS-4 stopping horizontal motion. The puncher will remain stationary while the punching cycle of operations is taking place.

When the puncher reaches the end of its horizontal movement, for instance, after punching the outermost tuyère, the striker 150 will close H-11 energizing HC-11. Contacts H-10A and H-10 are then closed energizing holding coil HC-10 which will remain energized until H-10 is broken by the return horizontal traverse of the puncher to the opposite end position. With the energizing of HC-11, contact H-9 is broken de-energizing HC-8 and HC-9 which breaks H-1 if UC-2 has previously been energized through opening of U-1 by closure of air valve 5 or by opening of U-2 as the result of restored air flow. If H-1 remains closed or again closes through action of U-2, the solenoid exhaust valve HS-1 and inlet valve HS-3 are operated through H-1, H-3, H-2, H-4 and H-6, pump motor 61 and pump 60 being actuated causing reverse horizontal motion of the puncher 12 whereby it will move from H-11 to H-10.

Movement of the switch striker 150 away from H-11 causes it to open de-energizing HC-11. Contacts H-6, H-8 and H-10A remain closed as long as holding coil HC-10 is energized through H-10 and H-10A. When switch striker 150 opens H-10, upon the return movement to its original end location, holding coil HC-10 is de-energized and contacts H-7 and H-9 are closed ready for the next horizontal traverse operation of the puncher. A dash pot 153, connected for operation as diagrammatically shown in dotted lines in Fig. 8, is utilized to cause sufficient time lag in breaking and making of contacts H-8 and H-9 to allow HC-8 and HC-9 to de-energize and open contact H-1.

Punching cycle of operations

Movement of the puncher 12 in position adjacent a tuyère whereby cam 70 is engaged, brings about closure of contact H-5 and P-1 and, inasmuch as H-1, P-2 and P-3 have previously been closed, solenoid valve PS-1 on control valve 155, as diagrammatically shown in dotted lines on Fig. 3 for operating the hydraulic punching cylinder 100, is energized admitting compressed

air to the cylinder starting the piston 105 on its punching stroke. Contacts S-2 and S-5 are open preventing movement of the puncher supporting frame 21 until they are closed. Contact M-1 is closed energizing MC-1 and preventing turning of the converter while the punching mechanism is connected thereto and punching tuyères. Contact H-4 is also open prohibiting horizontal motion of the puncher until it is again closed at the completion of the punching cycle. Contact P-3 is opened de-energizing PS-1 of control valve 155 but leaving the valve in punching operating position.

When piston 105 of punching cylinder 100 reaches the end of its punching stroke and closes P-4, this action energizes solenoid valve PS-2 of control valve 158 (Figs. 3 and 8) through circuits P-1, H-1, P-2 and P-4. Piston 145 of cylinder 110 is thereby actuated and moves to the right on its punching stroke, as illustrated in Figs. 3 and 8. Upon completion of the stroke, contact P-5 is closed energizing PC-5 thus breaking P-2 and closing P-6 and H-2A. These contacts are kept closed by the holding coil PC-6 until the puncher completes its punching cycle of operations and moves out of contact with cam 70. Closure of P-5 energizes PS-3, through P-1, H-1 and P-5, operating control valve 158 causing piston 145 of cylinder 110 to start the retracting stroke whereupon contact P-5 is opened de-energizing PS-3 and PC-5. When piston 145 of cylinder 110 is fully retracted P-7 is closed and solenoid valve PS-4, of control valve 155 for cylinder 100, is energized through P-1, H-1, P-6 and P-7 and piston 105 is caused to move to the left, as seen in Fig. 3, on its retracting stroke. At the end of the retracting stroke of piston cylinder 100, the lockout contacts S-2 and S-5 are closed. Contact M-1, however, is opened de-energizing MC-1 to allow turning or tilting of the converter, if necessary or desired. Conventional mechanism, not shown, is used to turn the converter. Contact P-3 is closed preparatory for the next punching stroke. Upon closure of H-4, horizontal movement of the puncher towards the next tuyère is initiated by energizing HS-1 and HS-3, HS-2 and HS-4, through H-1, H-3, H-2A, H-4 and H-6 or H-7. As the cam follower 160, diagrammatically illustrated in dotted lines on Fig. 8, leaves cam 70, contact H-5 is broken thereby de-energizing holding coil HC-5 closing contact H-2 and so continuing horizontal movement of the puncher when H-2A opens. Contact P-1 is also broken de-energizing PC-6 which opens contacts P-6 and H-2A de-energizing PS-4 whereas contact P-2 is closed making ready for the next punching cycle at a succeeding tuyère. If the converter operator wants the tuyères cleaned at any time during operation of the converter, this can be instituted by pushing manual switch button U-2A. When this is done the puncher will clean the tuyères automatically once across the converter.

Converter movement and control

In converter practise, a stack, not shown, is usually provided to carry away fumes. Accretions tend to accumulate within the stack and when the converter is turned out of stack, as in pouring, these accretions may drop down back of the converter. The falling accretions might result in damaging the tuyère puncher and associated mechanism if left in its normal tuyère punching position when turning the converter out

of stack. In accordance with the present invention, provision is made whereby the tuyère punching apparatus can be readily moved away from the converter when it is desired to turn the converter and avoid any possible damage being caused by falling accretions.

To move aside the puncher and operate the converter controls to turn it out of stack, as illustrated in the preferred arrangement of Figs. 2, 2A and 8, the operator places the converter turn-out controls in position to energize FC-2 which closes S-1 and when punching cylinder 100 reaches the end of its retracting stroke S-2 is closed and SS-1 is energized causing cylinder 44 to bring about movement of the puncher supporting frame 21, as shown in Fig. 2, whereby the punching apparatus is moved away from the converter to the position illustrated in dotted lines in Fig. 2. Contact S-2 is closed and M-1 is opened deenergizing MC-1 and closing M-2 whereby the converter is turned out of stack. During manipulation of the converter, it will be noted (Fig. 8) that contact H-3 is held open preventing horizontal motion of the puncher. As the converter turns out of stack the air supply valve 5 is closed which opens contacts U-1 de-energizing UC-1 opening U-3 and S-3. With contact S-3 broken the puncher and supporting frame 21 is retained in the position removed from the converter as shown in dotted lines in Fig. 2.

When the converter has been turned out of stack, the operator operates the control mechanism to de-energize FC-2 and open S-1. Contact S-4 is now closed but inasmuch as S-3 is open the puncher supporting frame 21 remains stationary. To turn the converter back into stack and restore the punching apparatus in position to automatically clean the tuyères, the operator adjusts the controller, not shown, to energize R-1 causing the converter to turn back into the stack. When the air to the converter tuyères is restored, contact S-3 closes and as the operator places the controller in neutral position S-1 is opened and S-4 is closed. As S-5 is already closed, SS-2 is energized and the puncher supporting frame 21 moves back to the position shown in full lines in Fig. 2. Contacts H-12, H-13 and H-14 are closed and the puncher then operates as before the converter was turned out of stack.

When it is desired to turn the converter, as is often necessary during operations, the controller is actuated to energize FC-2 or RC-2 which closes contact S-1 and, as soon as S-2 is closed by completion of the retraction stroke of cylinder 100, SS-1 is energized and the puncher supporting frame 21 starts to move to the right away from the converter, as illustrated in Fig. 2. When the converter has been turned to the desired position, the controller for the electrical circuit is returned to neutral which breaks contact S-1 and closes S-4 energizing SS-2 whereby the puncher and supporting frame 21 is moved back into punching position. Contact H-12 is then closed and the puncher operates as before turning the converter. Preferably a manual operating switch 165 is provided in the electrical control circuit, as shown in Fig. 8, which is utilized to energize coil 165-C and cause the puncher supporting frame 21 to move away from the converter in the same manner as energizing FC-2 or RC-2, the punching apparatus remaining back from the converter as long as this switch is closed.

Vertical motion control of puncher

Assume the converter is out of stack and the puncher supporting frame 21 moved away from the converter and it is desired to return the converter and tuyère punching machine to their normal position for automatic operation. The operator, referring to Fig. 8, re-establishes the electric circuit through M-2 energizing R-1 and RC-2 closing S-1. Inasmuch as M-1 is open and MC-1 is de-energized so that M-2 is closed, the converter turns back in stack and the air blast comes on closing S-3. After the converter has been turned into stack and the blowing of air through the tuyères in progress, the electrical control is adjusted to neutral whereby S-1 is opened and S-4 is closed. As contact S-5 is already closed, SS-2 is energized and the puncher supporting frame moves from the dotted line position shown in Fig. 2 to that shown in full lines. At the end of this movement, contact H-12 is closed.

To vertically align the puncher with the converter tuyères whereby the punching of the tuyères can be automatically performed, a photoelectric arrangement is provided as diagrammatically shown in Figs. 1, 5 and 9. An electric eye VR or VF, depending on the position of the converter, has its light source L-1 intercepted by either VR-1 or VF-1 which will energize VR-2 or VF-2 (see wiring diagram Fig. 8), holding H-14 open. The puncher is thus held inoperative until H-14 closes which will occur when the puncher is in vertical alignment with the converter tuyères. In the preferred arrangement illustrated the self-aligning mechanism operates as follows: Assume the interceptor plate VR-1 has intercepted light beam from L-1 to VR, VR-2 then becomes energized holding H-14 open. Closure of VR energizes solenoid valve coils VS-2 and VS-4 on vertical motion cylinder 35 causing pistons working in cylinder 35 to move upwardly carrying the piston rod 32, which is connected to the puncher supporting bed 18 through cable 31, counterweight 29 and cables 27 running over sheaves 28 as shown in Fig. 1. Upward movement of the piston in cylinder 35 causes the puncher supporting bed 18 to move downward whereby VR will in passing by the end of VR-1 receive light from source L-1 causing de-energizing of solenoid valve coils VS-2 and VS-4, which stops upward movement of piston in vertical motion cylinder 35, thereby bringing the puncher in alignment with the tuyères of the converter. When VR receives light VR-2 is de-energized closing H-14 starting punching cycle, provided the puncher was punching tuyères before converter was turned out of stack, or puts the puncher in proper position to begin punching cycle as soon as contact U-2 is closed.

Provision is also made for sounding an alarm should the light source L-1 fail. A suitable arrangement for accomplishing this electrically is illustrated in Fig. 8. As shown electric current flowing through the L-1, when it is lighted, energizes LC-1 which closes contacts L-3, L-4 and H-13 and opens L-2 energizing LC-2. The electrical circuit is completed by contact L-4 from VF to VS-1 and VS-3. L-3 completes circuit from VR to VS-2 and VS-4. Utilizing this arrangement, failure of light source L-1 de-energizes LC-1 opening L-4 and L-3 while closing contact L-2 which energizes LC-2 sounding alarm. Further, with the failure of

light source L-1, contact H-13 is opened stopping horizontal motion of the puncher, if underway, or locking out next punching cycle provided the puncher is not operating at the time of failure of the light source. If the puncher is in operation, it will complete its cycle and then remain inoperative until light source L-1 is again restored.

In the preferred embodiment, as shown, provision is made whereby the puncher may be made inoperative at any selected tuyère. To provide for this cam 70 adjacent each tuyère is made removable. Accordingly, if for any reason it is not desired to punch one or more particular tuyères, the cam 70 at each selected tuyère is removed whereby contacts P-1 and H-5 are not closed when the puncher moves adjacent the tuyère and passes on by to the next tuyère where cam 70 is in position to close contacts P-1 and H-5.

Modification using a plurality of punchers

Under certain conditions, for instance where there are a great number of tuyères which require punching, or it is desired to complete the punching or cleaning cycle in a shorter period of time, or both, a plurality of punchers may be used. A modification of the invention for doing this, using three tuyère punchers, is illustrated in Figs. 9, 10 and 11. A modified wiring diagram for controlling the operation of the multiple punchers on converters with unequal spacing of tuyères is shown in Fig. 12. In the construction of rotary converters the riding rings 170 on which the converter rotates and the ring gear 172 for drivingly connecting the converter for rotation to a prime mover, not shown, often necessitates unequal spacing of tuyères between groups of equally spaced tuyères.

This unequal spacing of tuyères does not interfere, of course, with the operation of a single puncher but when more than one is used provision should be made to accommodate for this construction. The preferred arrangement for adjustably controlling the relative movement between two tuyère punchers whereby they can be operated on the same converter and made to punch unequally spaced tuyères is illustrated in Figs. 9, 10 and 11. As shown, use is made of a hydraulic spacer 175 which is connected to the rack 180. The three punchers 12a, 12b and 12c move horizontally of the converter punching the tuyères 11 as controlled by cams 70. The punchers are moved by rack 180 which is fastened to and supported by the puncher 12b, as illustrated in Figs. 9 and 11, rack 180 being connected to puncher 12c by draw-bar 182. Tuyère puncher 12a is connected to the rack 180 through the hydraulic spacer 175, being fastened to the piston rod 176 of the piston 177 working in the cylinder 178 as illustrated in Fig. 11. In this connection it will be understood that a draw-bar similar to 182 may be used to connect punchers 12a and 12b in place of the hydraulic spacer 175, or a hydraulic spacer may be placed between punchers 12b and 12c, as desired depending upon the spacing arrangement of the tuyères on the converter which are to be punched.

In the schematic illustration of Fig. 11, rack 180, connected to the punchers, is in mesh with pinion 185 which is drivingly connected through pinion 186, keyed to the common shaft 188, to rack 190 fastened to and reciprocated by the piston rod 80 of the horizontal motion cylinder 65. Inasmuch as pinion 185 has more teeth than pinion 186, it will be seen that each movement

of the piston rod 80 is accentuated whereby the tuyère punchers 12a, 12b and 12c are moved a relatively greater distance than that of the piston rod in accordance with a fixed ratio. The horizontal motion cylinder 65 is operated by hydraulic fluid supplied by the pump 60 as heretofore described.

Hydraulic spacer operation

- 10 The hydraulic spacer 175, which is preferably constructed as shown in cross-section in Fig. 11, operates as follows: Assume the switch striker 150 is moving to the left (Fig. 11) toward the switch H-10 by actuation of piston rod 80 of the horizontal motion cylinder. The tuyère punchers 12a, 12b and 12c are also moving to the left in the arrangement shown, due to movement of the rack 180. Attached to the frame of puncher 12a is a spring brake 192 which contacts brake shoe 193 at the point where unequal spacing of tuyères begins. This brake stops movement of puncher 12a while cam follower 195 rides upon cam 196 opening valve 198. With valve 198 open, oil in hydraulic cylinder 178 on the right side of the piston 177 is forced to the left side of the piston. By varying the length of the cam 196 or distance through which valve 198 is open, the extent of movement of piston 177 relative to cylinder 178 may be controlled so that punchers 12a, 12b and 12c are brought to their respective tuyères at the same time as they are moved along to the left. During the movement, puncher 12a is held back momentarily at the point where unequal spacing of the tuyères starts and is pushed off the brake shoe 193 upon further movement of the rack 180 fastened to the punchers such that cam follower 195 rides off cam 196 and is moved in position to punch a tuyère, as desired, at the same time punchers 12b and 12c are positioned to punch their respective tuyères. When puncher 12a is to the left of cam 196 and moving to the right the hydraulic spacer operates in the same manner as described to compensate for the space difference in the opposite direction.
- 20 As piston rod 176 reciprocates forward and backward through the packing gland, some oil is inadvertently lost and is replaced from the oil reservoir 200 by way of check valves 201 located at opposite ends of the cylinder 178. To provide for equal displacement on opposite sides of the piston 177 for each increment of travel, the piston rod 176 is fastened to and extended through the piston and is fitted into the auxiliary cylinder 204, as illustrated in Fig. 11. Any leakage of oil past the piston rod is returned to the reservoir 200 through the conduit 205.

Description of electrical control circuit for punching tuyères using a plurality of punchers

- 30 An auxiliary electrical control circuit diagram for operating three punchers such as indicated at A, B and C, is illustrated in Fig. 12. The wiring circuit, as shown, may be tied in and made an auxiliary or branch circuit of that used for operating a single puncher as shown in Fig. 8. The modified circuit of Fig. 12 shows how the horizontal motion of three punchers, converter turning movement and puncher supporting frame movement are interlocked whereby proper sequence of converted and tuyère punching operations are effected and automatically controlled. It will be understood that the modified control circuit diagram shown in Fig. 12 may be used for automatically controlling the operation of two or more punchers, three being merely illustrative.

To simplify the circuit diagram and description only the contacts P-5 at the inner end of the punching cylinders 110 and contacts P-3, M-1, S-2, S-5 and H-4 at the outer end of the punching cylinders 100 are shown in Fig. 12.

Operating the punchers A, B and C employing the auxiliary control circuit of Fig. 12 in conjunction with the diagram circuit shown in Fig. 8, the sequence of operations is as follows: Assume the converter is in stack and the the punchers are in vertical alignment ready to clean the tuyères, with horizontal motion cylinder 65 at H-10 contact end of its stroke, air valve 5 (Fig. 8) for supplying air to converter open while contacts U-1 are closed energizing UC-1 closing U-3 and wherein all of the horizontal alignment contacts H-5 (Fig. 12) are open. When air flow to the converter falls off due to the tuyères gradually becoming crusted over with metal being blown, contacts U-2 (Fig. 8) close at a predetermined setting energizing coil UC-2 closing contacts H-1 which starts the motor 61 operating pump 60 supplying hydraulic fluid to horizontal motion cylinder 65 as illustrated in Fig. 9. This motor and pump continue to operate until contact H-1 is broken. The inlet valve HS-2 and exhaust valve HS-4 of horizontal motion cylinder 65 are opened, being actuated by energizing H-1, H-3, H-2, H-7 (Fig. 8) and the three interlocking H-4 contacts on the punchers A, B and C which electrical contacts are connected in series, as indicated in Fig. 12. When cylinder 65 is actuated moving the piston rod and attached switch striker 150 away from contact switch H-10, as shown in Fig. 9, it continues to move in this direction until the striker engages and operates switch H-11. During this movement H-1 is held closed by holding coils HC-8 and 9 to insure completion of movement from H-10 to H-11 in case contact U-2 should be closed by restored air flow to converter, HC-8 and 9 being energized through H-1 and H-9, as shown on circuit diagram of Fig. 8. When the horizontal movement of the punchers is completed in one direction and contact H-1 remains closed because of continued air demand or is again closed, the solenoid valves HS-1 and HS-3 are again energized through contacts H-1, H-3, H-2, H-6 and the three series connected H-4 contacts on the punchers A, B and C, as shown in Fig. 12. Pump 61 continues to operate or starts running as determined by contact H-1 and horizontal movement of the punchers in the opposite direction, for instance from H-11 to H-10, takes place as heretofore described in connection with circuit diagram shown in Fig. 8.

Horizontal movement of the punchers A, B and C is interrupted each time one or more of the punchers reaches a tuyère having cam 70 in place for initiating the punching cycle of operation. Stoppage of the horizontal motion is long enough to allow all the punchers to complete their punching cycle to clean their respective tuyères. When one or more of the punchers reaches a tuyère and cam 70 is engaged, contacts H-5 are connected in parallel (Fig. 12) are closed along with H-4, H-14, H-13 and H-12. Holding coil HC-5 is thus energized opening H-2 and deenergizing circuit through the series connected contacts H-4 on the punchers closing valves HS-1 and HS-3 or HS-2 and HS-4 stopping operation of horizontal motion cylinder 65. Each puncher at which a cam 70 is engaged then closes P-1 and the puncher performs its punching cycle automatically as previously described. Each puncher at the start of its punching cycle opens its respec-

tive H-4 contact. This prevents resumption of horizontal movement of the punchers until all H-4 contacts are again closed since the contacts H-4 of the three tuyère punchers are connected in series as illustrated in the circuit diagram of Fig. 12. Similarly, operation of the converter motor circuit is rendered inoperative until the contacts M-1 on all three punchers are opened. In the same manner, by connecting contacts S-2 in series and S-4 in series, movement of the puncher supporting frame 21 away from the converter is prevented until all the punchers have completed their tuyère punching and these series connected contacts closed.

Upon completion of the punching stroke, contacts H-2A at each puncher are closed. However, at any puncher which was not operated, due to withdrawal of tuyère cam 70, electrical connection is made through the by-pass circuit comprising contact H-2B which remains closed unless cam 70 is present to initiate punching cycle of operations. Provision of by-pass circuit for contact H-2A through contact H-2B completes the electrical connection so that the punchers can be automatically moved off their respective cams 70 as soon as all H-4 contacts are closed. It will be understood, of course, from the previous description that cams 70 for initiating the punching cycle of a puncher at a tuyère may be unequally spaced or equally spaced in groups with odd spacing between groups to correspond to the spacing arrangement of the tuyères.

In the normal operation of converters, there are periods, sometimes, when metallics are encountered. These metallics may tend to adhere to the punching bar, and, when punching tuyères under these conditions, heating means is preferably provided to heat the punch rod or bar 112 of the puncher to a temperature sufficiently high to prevent adherence of metallics to the punch bar. For example, means, not shown, may be arranged for heating the punch bar using a conventional gas or oil burner or electric heating arrangement.

The invention, as will be appreciated, provides a machine for automatically cleaning tuyères wherein the punching mechanism is free to move away from the converter when it is desired to permit manual cleaning of the tuyères. Further, sufficient flexibility in operation is provided whereby the puncher automatically aligns itself with the particular tuyère being punched. Utilizing the improved tuyère punching mechanism of the invention, the tendency of conventional punching rods to become stuck in tuyères, especially when the tuyère is out of alignment with the punching rod, has been practically eliminated under ordinary operating conditions.

While the preferred embodiment of the invention has been illustrated and described, it will be understood that various changes and omissions may be made by those skilled in the art without departing from the spirit and scope of the invention as defined by the claims.

What is claimed is:

1. Apparatus for punching converter tuyères comprising in combination, a punching tool, mechanism for reciprocating said tool while in registry with a tuyère to clear the latter of encrustations, a base movable relative to the converter, universally yieldable mounting means supporting said reciprocating mechanism and punching tool on said base and rendering the tool self-aligning to the particular tuyère with

which it is in registry during punching thereof, and means for moving said base to shift said tool and associated mechanism as a unit towards and away from said converter, said base-moving means being pivotally mounted on a carriage supported independently of the converter.

2. In apparatus for punching converter tuyères, a punching tool, means for reciprocating said tool while in registry with a tuyère to clear the same of encrustations, said punching tool and associated reciprocating mechanism being mounted for universal movement on a base which is movable relative to said converter, a carriage supported independently of the converter, means for moving said base to shift said tool and associated mechanism as a unit towards and away from said converter, said base-moving means being pivotally mounted on said carriage and in turn supporting said base, means for moving said carriage longitudinally of said converter from tuyère to tuyère successively and automatically, and means for adjusting the position of said carriage vertically with respect to said converter to bring said punching tool in registry with the tuyère to be punched.

3. A tuyère punching machine of the class described comprising a frame structurally independent of the converter to be punched, said frame being supported for movement on a track extending at a right angle with respect to the converter, means for moving said frame on said track toward and away from the converter, guideways carried by said frame, a machine bed disposed longitudinally of the converter and mounted for vertical movement along said guideways, a carriage supported on said machine bed, means for moving said carriage along the machine bed, punching tool mechanism mounted on said carriage, means for actuating said punching tool upon arresting the movement of said carriage at predetermined stations along said machine bed, and means for stopping the moving carriage automatically at said predetermined stations.

4. Apparatus for punching tuyères comprising primary and secondary cylinders and piston actuated mechanism, said primary cylinder and piston mechanism being arranged to reciprocate a punching tool while said tool is in registry with a tuyère, said secondary cylinder and piston mechanism being operatively connected to move said primary cylinder and associated punching tool as a unit towards and away from the tuyère whereby the tuyère can be cleared of encrustations by a stroke of said punching tool as actuated by said primary cylinder that is of lesser length than that of the tuyère.

5. In apparatus for punching converter tuyères, a frame supported for movement relative to the converter, means for moving said frame with respect to the converter, vertically disposed guideways arranged at the opposite ends of the frame, a machine bed positioned for movement in said guideways, a carriage supported for movement on said bed, means for moving said carriage along said machine bed, a punching tool and reciprocating mechanism therefor mounted on said carriage, electrically operated means for automatically adjusting said machine bed relative to the converter tuyères, means responsive to decreased air flow to the converter for initiating the movement of said carriage from tuyère to tuyère, and electrically controlled means for automatically punching the tuyères in succession

to remove encrustations and increase the air flow to the converter.

6. Apparatus for punching converter tuyères comprising in combination, a frame having a carriage supported for movement relative to the frame, tuyère puncher mechanism mounted on said carriage, means for positioning the puncher so that individual tuyères may be automatically punched, means for moving said frame towards and away from the converter, a platform carried by said frame, and means for adjustably extending said platform towards the converter while retained by said frame to permit manual punching of the tuyères.

15. 7. In combination, a rotary converter having electrical control mechanism for turning the converter out of stack and tuyères through which air is admitted to the converter, a frame extending longitudinally and vertically for arrangement alongside the converter adjacent the tuyères,

20. means for moving said frame towards and away from the converter, a carriage carried by said frame, said carriage being movable longitudinally and circumferentially relative to said frame, a punching tool and mechanism for actuating said

25. tool to punch encrustations from the inner end of individual tuyères, means for automatically effecting step-by-step movement of said carriage and associated punching mechanism from tuyère to tuyère, electrically controlled mechanism for bringing the punching tool into position whereby said punching tool is in registry with a tuyère to be punched, and means operable upon positioning of the carriage at the tuyère to be

30. punched to render inoperative the electrical control mechanisms for turning said converter and for moving the puncher supporting frame and the punching tool carriage, until after the punching operation is completed and the punching tool 40. removed from the tuyère, whereby inadvertent relative movement with resultant damage to the parts is avoided.

8. In apparatus for punching converter tuyères, a punching tool, mechanism for reciprocating

45. said tool to punch encrustations from the tuyère, said tool and reciprocating mechanism being mounted on a base that is movable with respect to the converter, and means for reciprocating said base to move said punching tool and its reciprocating mechanism as a unit toward and away from the converter, said last-mentioned means being adjustable with respect to said base whereby the extent of penetration of the punching tool in the tuyère can be varied to compensate

55. for tuyère erosion accompanying continued use of the converter.

9. In apparatus for punching tuyères, a punching tool, means for reciprocating said tool in a tuyère to clear the same of encrustations, said

60. punching tool and associated reciprocating mechanism being yieldably mounted on a carriage supported independently of the converter, means for moving said carriage from tuyère to tuyère successively and automatically, means for stopping the carriage at a tuyère to be cleaned and initiating operation of said tool to punch said tuyère, and means for starting the sequence of operations including movement of the puncher carriage in position to perform the punching operation and punching of the tuyères throughout the length of the converter responsive to a predetermined decrease in air flow to the converter occasioned by the formation of encrustations on one or more tuyère ends interior of the

70. converter.

10. In apparatus for punching converter tuyères, a punching tool, mechanism associated with said tool for reciprocating the latter while in registry with a tuyère to clear it of encrustations, and means yieldably supporting said punching tool and its said reciprocating mechanism and permitting their movement as a unit universally relative to the converter in response to a change in position of the punching tool after entering the tuyère and occasioned by the position of the latter, whereby the punching tool automatically adjusts itself to the alignment of the tuyère during punching thereof.

11. In a tuyère punching machine of the class described: the combination with a carriage movable laterally and vertically with respect to a converter, a punching tool supported on said carriage, and means for reciprocating said tool while in registry with a tuyère to clear the latter of encrustations, of means mounting said punching tool and reciprocating means for universal movement relative to the converter and carriage in response to a change in position of the punching tool in conforming to the bore of the tuyère during punching thereof, whereby the punching tool is self-aligning with respect to the tuyère after said tool has been brought in registry with the tuyère to be punched and the punching operation initiated.

12. In a tuyère punching machine of the class described: a carriage movable laterally and vertically with respect to a converter, a punching tool supported on said carriage, means for reciprocating said tool while in registry with a tuyère to clear the same of encrustations, said punching tool and reciprocating means being mounted for universal movement relative to the converter whereby the punching tool is self-aligning with respect to the tuyère after said tool has been brought in registry with the tuyère to be punched and the punching operation initiated, means for automatically bringing said punching tool in position for insertion in the tuyère to be punched, and mechanism operable to prevent movement of either the carriage or converter until the punching tool has completed its punching operation and has been withdrawn from the converter tuyère.

13. Apparatus for punching the tuyères of a converter, said punching apparatus comprising a frame extending vertically and longitudinally of the converter and affording access to the tuyères thereof, said frame being supported for movement towards and away from said converter, means for moving the frame, a carriage mounted on said frame and arranged for longitudinal and vertical movement thereon whereby the carriage is brought adjacent the converter tuyères, a punching tool, including means for reciprocating the tool, mounted on said carriage, means for automatically positioning the punching tool in vertical alignment with a tuyère which is to be punched, means for moving said carriage and associated punching mechanism mounted thereon horizontally in said frame from tuyère to tuyère, means for causing the operation of said punching tool to punch individual tuyères, and mechanism for interlocking said frame moving means, carriage moving means and punching mechanism whereby said frame and carriage moving means are rendered inoperative during operation of said punching mechanism to punch a tuyère.

14. Apparatus for punching the tuyères of a converter, said punching apparatus comprising a

frame extending vertically and longitudinally of the converter and affording access to the tuyères thereof, said frame being supported for movement towards and away from said converter, means for moving the frame, a carriage mounted on said frame and arranged for longitudinal and vertical movement thereon whereby the carriage is brought adjacent the converter tuyères, a punching tool, including means for reciprocating the tool, mounted on said carriage, means for automatically positioning the punching tool in vertical alignment with a tuyère which is to be punched, means for moving said carriage and associated punching mechanism mounted thereon horizontally in said frame from tuyère to tuyère successively and automatically, means for stopping the carriage at a tuyère to be punched, means for initiating the operation to punch said tuyère, means responsive to decreased air flow to the converter tuyères to start the tuyère punching cycle of operations, and means responsive to restoration of air flow to the converter to a predetermined value to discontinue the tuyère punching cycle of operations.

15. In combination, a metallurgical converter having tuyères, a frame structure supported separately but adjacent to said converter, mechanism including a tuyère punching member adapted to be inserted into a tuyère, means to reciprocate said member, a carriage upon which said mechanism is yieldably mounted whereby said member and associated reciprocating means may move universally relative to said carriage and self align itself with the tuyère being punched to obviate binding and sticking of the punching member in the tuyère, means including photoelectrically actuated mechanism for automatically positioning said carriage relative to a tuyère to be punched, and cam actuated mechanism for initiating the insertion and reciprocation of said tuyère punching member in the tuyère.

16. In apparatus for punching tuyères on a converter, a frame extending longitudinally of said converter affording access to the tuyères of the converter, a plurality of carriages arranged for vertical and longitudinal movement on said frame and adjacent said tuyères, said carriages being supported on a common machine bed which machine bed is arranged to move vertically in said frame, tuyère punching mechanism mounted on each carriage for punching said tuyères, means for moving the carriages automatically and simultaneously along said machine bed from tuyère to tuyère, and means engageable by said carriages adjacent each tuyère to be punched to halt the carriage movement and actuate punching control mechanism to punch the tuyère whereby a plurality of tuyères are punched concurrently.

17. Converter tuyère punching apparatus comprising a frame, a machine bed arranged for vertical movement in said frame, means comprising pulley and counter-balanced cable mechanism for supporting said machine bed in the frame, means for moving said machine bed vertically, electrically controlled mechanism for positioning the machine bed in said frame adjacent the tuyères to be punched, tuyère punching tool mechanism mounted on a carriage which is supported for movement relative to the converter and adjacent the tuyères, electrically controlled mechanism for causing said carriage to move longitudinally of said machine bed and in posi-

tion to punch the tuyères one after the other from one end of the converter to the other, and means for interrupting the longitudinal movement of the carriage at each tuyère to be punched during the actual punching thereof.

18. Apparatus for punching converter tuyères comprising a movable support, a plurality of tuyère punchers arranged for movement along said support and adjacent said converter tuyères, each of said punchers comprising a punching tool mounted for universal movement relative to the converter thereby permitting self-alignment of tool to tuyère during punching thereof, common means for moving said plurality of punchers automatically and simultaneously in position to punch individual tuyères, and means for selectively actuating one or more of said punchers concurrently to clear encrustations from the tuyères.

19. Apparatus for punching converter tuyères comprising a plurality of punchers, means for concurrently moving said plurality of punchers in position to punch a selected number of tuyères at the same time, means for initiating the punching cycle of operations for each puncher whereby the respective tuyères adjacent the punchers are punched, and means for initiating the movement of said punchers from tuyère to tuyère after each punching cycle, said movement initiating means being prevented from operating until all of the punchers have completed their respective punching cycles of operation.

20. In an apparatus for punching unequally-spaced converter tuyères, a plurality of punchers, common means for moving said punchers concurrently from tuyère to tuyère, spacer means operable at the point where unequal spacing of the tuyères is encountered during movement of said punchers to compensate for the spacial difference in the movement of one or more punchers whereby all of the punchers are moved in position to punch their respective tuyères at the end of each intermittent moving cycle as the punchers are moved from tuyère to tuyère successively.

21. An apparatus for punching tuyères according to claim 20 wherein the spacer means comprises an hydraulic cylinder and co-acting brake operable to interrupt the travel of a puncher at a predetermined point until the spacial difference between the tuyère spacings have been made up then permitting said last mentioned puncher to move in unison with the remaining punchers whereby all the punchers are simultaneously brought in proper position for punching their respective tuyères.

22. In an apparatus for punching converter tuyères, the combination of a carriage support,

a carriage movable on said support longitudinally of the converter and adjacent the tuyères, said support and carriage being movable as a unit vertically with respect to the converter, a tuyère puncher mounted on said carriage, said puncher comprising a punching rod for inserting into a tuyère and a plurality of piston actuated means for moving said punch rod to punch a tuyère.

5 23. In apparatus for punching the tuyères of a rotary converter, a frame, a carriage support on said frame, a carriage movable on said support, a punching tool on said carriage and means for reciprocating said tool when inserted in a tuyère, electrically operated mechanism for moving said carriage on said support longitudinally of the converter and adjacent the tuyères to be punched, electrically operated mechanism for moving said carriage and support as a unit circumferentially of the converter, and means operable in response to a predetermined decrease in air flow to the converter through the tuyères to initiate the movement of said carriage longitudinally of the converter and automatic punching of the tuyères successively throughout the length of the converter.

25 24. A puncher for automatically punching tuyères of a converter comprising a plurality of fluid actuated pistons one of which is connected to and arranged to reciprocate a punching tool while in registry with a tuyère, said punching tool actuating piston and tool being yieldably mounted on a base member which is connected to and reciprocated by a second fluid actuated piston.

30 25. In tuyère punching apparatus, the combination with a base, and a punching tool with reciprocating means therefor mounted on said base, of means for adjustably positioning said base toward and away from the tuyère to control the extent to which the punching tool is inserted into the tuyère by said reciprocating means.
